UNITED STATES PATENT OFFICE.

ISIDORE MARSHAK, OF BROOKLYN, NEW YORK, ASSIGNOR TO ALEXANDER AMITIN, OF BROOKLYN, NEW YORK.

DESIGN FOR A FERN STAND.

Application filed February 4, 1928. Serial No. 25,197. Term of patent 3½ years.

To all whom it may concern:

Be it known that I, ISIDORE MARSHAK, a citizen of the United States, and a resident of the borough of Brooklyn, Kings County, city and State of New York, have invented a new, original, and ornamental Design for a Fern Stand, of which the following is a specification, reference being had to the accompanying drawings, forming a part hereof.

Referring to the annexed sheet of drawings,

I claim:

The ornamental design for a fern stand, substantially as shown.

ISIDORE MARSHAK.
